(57) **CLAIM**

The ornamental design for a grip for a handle for a hitch ball assembly for a gooseneck hitch, as shown and described.

DESCRIPTION

FIG. 1 is a top, front perspective view of a grip for a handle for a hitch ball assembly for a gooseneck hitch shown in use; FIG. 2 is a top, front perspective view of the grip for a handle for a hitch ball assembly for a gooseneck hitch shown in a second state of use;

FIG. 3 is a bottom, rear perspective view thereof;

FIG. 4 is a front elevational view thereof;

FIG. 5 is a rear elevational view thereof;

FIG. 6 is a left-side, elevational view thereof;

FIG. 7 is a right-side, elevational view thereof;

FIG. 8 is a top plan view thereof; and,

FIG. 9 is a bottom plan view thereof.

The broken lines illustrate environmental structure, in the nature of a hitch ball assembly for a gooseneck hitch including a handle on which the grip is mounted and which forms no part of the claimed design.
